DEVICE FOR APPLYING RUBBER BANDS

Walter W. Camp, Castorland, N. Y.

Application November 8, 1939, Serial No. 303,470

2 Claims. (Cl. 100—31)

My invention relates to improvements in devices for applying rubber bands, the principal object in view being to provide a practical, easily operated, device for stretching such bands and placing the same around small articles such as boxes, or packages, so as to obviate the arduous performance of such operations by hand.

Another object is to provide a device of the character and for the purpose above set forth which is of simple construction, adapted to withstand continuous and rough usage, and inexpensive to manufacture.

To the accomplishment of the above, and subordinate objects presently appearing, a preferred embodiment of my invention has been illustrated in the accompanying drawings, set forth in detail in the succeeding description, and defined in the claims appended hereto.

In said drawings:

Figure 1 is a view in front elevation of the preferred embodiment of my invention,

Figure 2 is a view in top plan,

Figure 3 is a view in side elevation,

Figure 4 is a fragmentary view in vertical section taken on the line 4—4 of Figure 3 looking in the direction indicated by the arrows, and drawn to an enlarged scale, and

Figure 5 is a view in transverse section taken on the line 5—5 of Figure 1 looking downwardly as indicated by the arrows.

Referring to the drawings by numerals, preferably the operating parts of my improved device are supported by a tripod-like frame comprising rod-like legs 1 inwardly off-set at their upper ends, as at 2, and secured at the upper extremities thereof, in equi-distantly spaced relation, in a disk-like plate 3 as by nuts 4. The plate 3 is apertured centrally as at 5. A pair of flat hanger rods 6 depend from the plate 3 in edgewise spaced-apart relation, said rods having upward terminals 7 extending through the aperture 5 with cotter pins 8 extending through the same above said plate whereby said rods are suspended from said plate. Shoulders 9 on the rods 6, below the plate 3, prevent upward movement of said rods in the aperture 5. The hanger rods 6 terminate at the lower ends thereof substantially midway of the legs 1 and support in pendant position a pair of laterally spaced bearing plates 10 secured adjacent the upper edges thereof to the lower ends of said rods 6 in centered position thereon by rivets 11, said ends of the rods 6 being interposed between said plates 10 and thereby spacing the same apart. The bearing plates 10 are of sub-

stantially rectangular form with the exception of the upper corners thereof which are beveled, as at 12, for a purpose presently seen.

Interposed between the hanger rods 6 and plates 10 and guided by said rods 6 for vertical reciprocating movement is an operating rod 14 having a ball member 15 fast on the upper end thereof above the terminals 7 of the rods 6 and also having an enlarged elongated, lower, flat end 16 fitting sidewise between the plates 10 and having toothed opposite edges 17 forming a duplex rack member.

The toothed edges 17 mesh with a pair of toothed sector-like ends 18, respectively, of a pair of band-stretching and applying fingers 19, the ends 18 of which are rotatably mounted between the bearing plates 10 on opposite sides of the end 16 of said rod 14 and adjacent to the lower corners of said plates 10. Studs 20 riveted in the plates 10 and extending through the ends 18 of said fingers 19 provide for mounting said fingers. The band-stretching and applying fingers 19 are of sufficient length to extend at the free ends 21 thereof above the top edges of the plates 10 for a slight distance and are normally held under the weight of the operating rod 14, and end 16 thereof, in upstanding position as shown in full lines in Figure 4, with said free ends 21 thereof abutting the outer side edges of the hanger bars 14 whereby the normal position of said fingers 19 is established, likewise the normal lowermost position of the operating bar 14.

In this normal position of said fingers 19, the free ends 21 thereof are located within the lower end of a transversely oval, tubular spool member 22 interposed between the plate 3 and the top edges of the plates 10 in surrounding relation to the hanger bars 6 and the operating bar 14 and fitting endwise between the plate 3 and said edges 20 of the plates 10. The spool member 22 has formed, in the lower end thereof, a pair of opposed inwardly extending slots 23 in the plane of said fingers 19 permitting the free ends 21 of said fingers to pass into and out of said spool member. The spool member is designed to carry a plurality of rubber bands 24 fitting around the same in superposed relation thereon. The band-stretching and applying fingers 19 are each notched, as at 25, in one edge thereof adjacent the free end 21 of the finger, said notches being in the normal position of the fingers opposite the slots 23 and opening outwardly of the latter.

A lever 26 and pull chain 27 are provided on top of the plate 3 to move the operating rod 14

upwardly. The lever 26 has a forked inner end 28 straddling the operating rod 14 beneath the ball member 15, and is pivoted intermediate the ends thereof, as at 29, on a pair of ears 30 upstanding from said plate 3. The pull chain 27 is connected to the outer end of the lever 26 in any suitable manner and equipped with a finger ring 31. Obviously, by pulling on the chain 27, the lever 26 may be rocked to elevate the operating rod 14 and such movement of said rod will result in rotation of the band-stretching and applying fingers 19 outwardly and downwardly from their described normal position.

A pair of outwardly bowed band-stretching rods 32 are provided upon opposite sides of the pair of bearing plates 10, respectively, to depend therefrom for a substantial distance below the same, said rods having upper ends suitably attached to the upper edges of said plates 10, respectively, and being spaced apart at the lower ends thereof.

Referring now to the operation of the described device. With the parts in the described normal position, the device is stood on a table, or the like, and a package or box, represented at 33 is placed below the pair of plates 10 and between the rods 32 in the vertical center of the device approximately. A rubber band 24 is pushed down the spool member 22 over the slots 23. The operating rod 14 is next raised by means of the pull chain 27 and lever 26. Under such movement of said rod 14 and the toothed edges 17 of end 16 thereof the sector-like ends 18 of the band-stretching and applying fingers 19 are rotated oppositely in the directions indicated by the arrows in Figure 4, i. e., outwardly and downwardly. Under such rotation of said ends 18, said fingers 19 are moved to swing the free ends 21 thereof out of the spool member 22 by way of the slots 25. The free ends 21 as they move out of said slots 23 pick up the rubber band 24 in the notches 25. Under continued rotation of said fingers 19, said band is stretched in opposite directions and carried down over the rods 32 which open up the band so that under such stretching and opening said band is carried downwardly in surrounding relation to the plates 10 until it is positioned around the package 33. At this point, the band-stretching and applying fingers 19 are downturned and the position of the notches 25 is reversed from normal, said notches now opening inwardly toward the package 33 so that the rubber band is released to snap around said package. It will of course, be understood, that the notches 25 are so shaped as to retain the band on the fingers 19 until the latter are in the described downturned release position, and that said release position is reached by said fingers as the band is carried beyond the lower ends of the rods 32. Upon release of the pull chain 27 the parts will return to the normal positions described in the foregoing and in a manner which will be clear

from the foregoing. In the returned positions of the parts, another band may be pushed down on the spool member 22 for application in the manner described.

5 The foregoing will, it is believed, suffice to impart a clear understanding of my invention without further explanation.

Manifestly the invention, as described, is susceptible of modification without departing from 10 the inventive concept and right is herein reserved to such modifications as fall within the scope of the subjoined claims.

What I claim is:

1. A device for applying rubber bands to packages and the like comprising a frame including legs adapted to straddle a package and having a top, a pair of band-stretching and applying members suspended from said top for location over the package, said members being swingably mounted for outward and downward movement about fixed axes to pick up and stretch bands in one direction encircling the same and release said bands around the package, a spindle-like band holder depending endwise from said top in fixed position with a terminal end thereof located over said members and adapted for holding a plurality of bands for manual feeding downwardly thereon into encircling relation to the members, manipulative means for swinging said members comprising a vertical operating rod extending through said top, and a rack on said rod geared to said members, and operative upwardly by said rod to impart outward and downward swinging movement to said members, 25 and a pair of outwardly bowed band stretching rods extending downwardly from the lower end of said holder for stretching the bands in a direction at right angles to the direction in which they are stretched by said members.

2. A device for applying rubber bands to packages and the like comprising a frame including legs adapted to straddle a package and having a top, a pair of band-stretching and applying members suspended from said top for location over the package, said members being swingably mounted for outward and downward movement about fixed axes to pick up bands encircling the same and release said bands around the package, a spindle-like band holder depending endwise from said top in fixed position with a terminal end thereof located over said members and adapted for holding a plurality of bands for manual feeding downwardly thereon into encircling relation to the members, and manipulative means for swinging said members, said members being notched to hold the picked-up bands thereon until said bands are in surrounding relation to the package, and said manipulative means being operative upwardly to impart outward and downward swinging movement to said members.

WALTER W. CAMP.
